FORMS SPLICING MACHINE

William H. Rives, Columbia, S. C., assignor to Universal Business Machines, Inc., Columbia, S. C., a corporation of South Carolina

Application August 9, 1956, Serial No. 602,969

13 Claims. (Cl. 154—42.3)

This invention relates to machines of the type for 15 splicing two sheets of material together by applying a strip of adhesive tape thereto.

Although machines of this general type are broadly old, the objectives of this invention are to provide improvements and refinements in certain constructions of the devices of this nature including the provision of means for automatically severing the proper length or strip of tape and performing such severing operation in timed relation to the splicing operation itself, means for presetting the severing means during the initial stage of the cycle of splicing operation and means for locating and pretensioning the sheets which are to be spliced, and including a device for holding the sheets down to ensure their engagement by the locating means in opposition to the pull of the splicing tape against the sheets during the splicing operation.

Figure 1 is a side elevation, partly in section, illustrating the splicing machine and showing the relationship of parts during a splicing operation;

Figure 2 is a horizontal section taken along the plane of section line 2—2 of Figure 1;

Figure 3 is an enlarged top plan view of the upper pivot showing details of the knife releasing mechanism;

Figure 4 is an end elevation of the assembly shown in Figure 3;

Figure 5 is an elevational view of the lower portion of the carriage showing the relative positions of the support roller and serving knife;

Figure 6 is a partial section similar to Figure 2 but showing the position of parts near the end of a severing operation; and

Figure 7 is a plan view showing the presser foot in position holding down the sheets being spliced.

Referring now to Figure 1, reference character 10 indicates the base or table which supports the sheets to be spliced and which is preferably provided with suitable feet or standards 11 for supporting the base in elevated position to provide clearance for those portions of the device which project below the base. Pivoted mounted at one end of the base is a supporting and guiding arm 12 and pivoted to the upper end of this arm is the carriage assembly 13, the arm and carriage roughly describing an inverted V.

The base also supports a vertical guide or cam plate 14 adjacent arm 12 as well as a presser foot assembly 15 (Figures 1 and 7). Two rows of locating pins or studs 16 and 17 are arranged across the table in parallel rows spaced apart approximately the same distance as are the two rows 18a and 18b of marginal holes along the sides of the two form sheets 19 and 20 which are to be spliced, see particularly Figures 2, 6 and 7.

The pins 16 are rigidly fixed to the base whereas the pins 17 are fixed to a plate 21 supported horizontally below base 10 and project upwardly through holes in the base 10. Plate 21 is pivotally supported upon a U-shaped bracket 22 secured to the under face of base 10, by a pair of pins 23 extending from the ends of the plate,

2

near its rear or inner edge, through bearing holes in the ends of the arms of bracket 22. Plate 21 is provided with a depending lever arm 24 near its middle, and a tension spring 25 is connected between the lower end 5 of this arm and the bracket 22 to normally bias the plate 21 and pins 17 such that the upper ends of the latter, which project through oversize holes in the base, will normally assume a position spaced from fixed pins 16 a distance slightly greater than the spacing between the opposite marginal holes 18a and 18b of sheets 19 and 20. Thus, when the two sheets are engaged over the pins, they will be under slight tension from spring 25, tending to smooth and flatten the sheets in a transverse direction.

The guide arm 12 has a cross-head 26 the opposite ends of which are provided with bearings receiving pivot pins 27 and 28 which are threaded through upstanding leg portions 29 and 30 of a pair of L-shaped brackets 31 and 32 which are fixed to opposite edge portions of the table or base 10. Pins 27 and 28 are provided with lock nuts 33 and 34 to hold them in correct adjusted position.

Figures 1, 3 and 4 illustrate the upper end construction of the guide arm and the manner for pivotally attaching the carriage thereto. A split-ring clamp 35 is 25 clamped on the guide arm 12 near its upper end by means of the clamp bolt 36 and rigid with this clamp ring are a pair of parallel arms 37 and 38 which extend at an angle to arm 12 and straddle a cross-bar member 39 attached to the upper end portion of a tubular rod 40 30 which forms part of the carriage assembly 13 and interposed between the opposite ends of this cross-bar and the arms 37 and 38 are the terminal portions 41 and 42 of a U-shaped latch release carrier designated generally by the reference character 43. The rod 40 is pivotally connected to the arm 12 by a pair of pivot pins 44a and 44b threaded through the arms 37 and 38, passing through holes in arms 41 and 42 and entering bearing sockets in the ends of cross-bar 39. This provides a pivotal connection between the upper end of the guide arm 12 and the carriage assembly 13.

An adjusting strap 47 has one end thereof secured to the clamp ring 35 by the bolt 36 and extends therefrom alongside the latch release carrier 43 which carries a clamping screw 48 engaged through an elongate slot 49 45 in the strap so as to adjust the ultimate position of the latch release carrier 43, for a purpose which will become presently apparent.

The carriage 13 consists essentially of a side wall plate 50 which is rigidly affixed to the tubular rod 40 and which 50 is provided with a laterally projecting flange 51 defining a compartment for enclosing the various parts of the carriage, it being understood that a suitable cover plate (not shown) is to be arranged parallel to but spaced from the side wall 50 and being removably attached to 55 the outer edge of the flange 51. Mounted on the plate 50 is a reel 52 for carrying a standard roll 53 of conventional adhesive type splicing tape. The carrier also includes a suitable handle such as the T-shaped handle 54 for manipulation of the carriage, as will be described 60 below.

Secured to flange 51 at the lower portion of plate 50 is a mounting plate 55 arranged parallel with but spaced from plate 50, see particularly Figures 1 and 2. A pair of stud members 56 and 57 extend out from the rear face 65 of plate 55 and form mounts for spring fingers 58 and 59 respectively, the construction of which is shown in Figures 1, 2 and 5. As shown in Figure 1 leaf spring 59 extends downwardly and rearwardly from stud 57 to a point beyond the end of spring 58 and serves to press the adhesive tape against the forms to be spliced. As shown in Figure 5, leaf spring 58 is bifurcated to present the spaced leg portions 58a and 58b which engage the under surfaces

of opposite marginal edge portions of the main tensioning and applying spring 59. The splicing tape 62 is fed between the two leaf springs 58 and 59, and from Figure 1, it will be evident that terminal portions of the spring legs 58a and 58b will lightly engage this tape against the undersurface of the applying spring 59 and will thus serve to hold the tape in position ready for use. For preventing lateral movement of the tape from between the fingers, spring 59 is notched on opposite edges near its lower end; see Figure 5, and narrow end portions 58a' and 58b' of fingers 58a and 58b are turned or bent into these notches, as shown in Figure 1.

Integral with the mounting plate 55 is a depending leg portion 63 located to the rear of spring 58 and supporting a transverse shaft 64 at its lower end. A roller 65 of resilient material is journaled upon one end portion of the axle shaft 64 which projects from one side of arm 63. The opposite end of shaft 64 serves to guide the movement of carriage 13 in a manner described below. A screw 64a retains roller 65 on shaft 64.

Also mounted on the supporting plate 55 is a spring biased knife assembly including the generally sector-shaped lever arm 67 pivoted at its apex to the mounting plate 55 by screw 68, and carrying the knife blade 69 extending laterally from its curved edge portion, the knife blade being provided with a curved cutting edge, as will be seen most clearly in Figures 1, 2 and 6. The knife blade 69 is secured to the arm 67 by means of a securing screw 70 threaded into a laterally projecting portion 71 of the arm, as is shown most clearly in Figures 5 and 6, and the arm 67 also carries a laterally projecting camming pin 72, the purpose of which will be presently apparent. The knife blade is normally urged to a tape severing position shown in Figures 5 and 6 by tension spring 73 secured between a free end portion of the arm 67 and a portion of the carriage plate 50. The arm 67 also carries a latching hook 74 engageable with a hooked pawl member 75 mounted on the back side of plate 55 which has been broken away in Figure 1 to show the location of the pawl. The rear end of pawl 75 is pivoted at 76 to the mounting plate 55 and urged by the spring 77 into latching engagement with the hook 74 to hold the severing blade assembly in its raised or cocked position against the pull of spring 73. Upon release of pawl 75, the blade mounting will be snapped by its spring 73 into normal position and during such course of movement the blade 69 will sever the tape 62 at the end of a splicing operation.

To effect proper timed release of the knife blade assembly, the previously mentioned tubular rod 40 is provided with plugs in each end having aligned bores through which is slidably received a rod 78 having its lower end bearing against the pawl 75 and which, when urged downwardly, will move the pawl so as to release the knife blade assembly. To effect movement of the rod 78, in proper timed relationship with the movement of the carriage during the splicing operation, the upper end of the rod 78 is bent back upon itself with the terminal end 79 thereof received in a bore in the upper end plug of the rod 40, leaving the loop portion 80 of the trip rod projecting from the upper end of the rod 40. The previously mentioned latch release carrier 43 is provided with a threaded cam screw 81 which is threaded through the bight portion thereof so that the inner end 82 is engageable against and depresses the loop 80 when the carriage 13 has been moved to the left in Figure 1 to near the end of the splicing operation. To effect proper timing of the release operation, it is to be noted that the release carrier 43 may be swung toward and away from the trip rod loop 80 by virtue of its pivotal mounting on the pivot pins 44a and 44b, and any adjusted position thereof may be fixed by means of the screw 48 engaging the strap 47, the screw 81 having the lock nut 83 to hold the

screw in adjusted position to assure engagement thereof with the rod loop 80.

The previously mentioned cam plate 14 is fixed to the base by means of an L-shaped bracket 84 and this cam plate carries a pair of flanges 85 and 86 projecting laterally from the rear face of the plate and defining a cam track 87 therebetween which is adapted to receive and guide the rear end of axle 64 which also serves to carry the roller 65. Normally, the ready position for the carriage is one in which the rear end of the axle 64 is engaged within the crook 88 at the upper end of the lower cam track lip or flange 86, it being appreciated that when the parts are in this position, the center of gravity of the parts pivoting about axis 28 will be located to the right of this axis and the weight of the assembly will maintain the end of the axle 64 within the crook 88. The purpose of the cam track is not only to guide the carriage 13 so as to apply the tape at the proper point on the two sheets which are to be spliced, but also to cooperate with a cocking member 89 which effects movement of the knife blade assembly from its normal to its cocked or latched position by the downward and forward movement of the carriage. The cocking member is a bell-crank lever pivoted intermediate its ends by suitable pin 90 to the cam plate 14 and is normally urged by spring 91 so that the cocking leg 92 thereof is upstanding and its stop leg 93 is in a horizontal position with its end resting upon the upper surface of the upper cam track flange 85. When the parts are in this position, as the axle 64 is moved down the cam track 87, the cocking pin 72 extending laterally from the knife blade assembly will first engage the upper edge of leg 93 of the cocking lever when its downward movement will be arrested. During continued movement of the axle down the cam track, the knife blade arm will begin rising toward its cocked position. As the carriage continues its downward and forward movement, the final movement of the blade assembly is accomplished when pin 72 engages leg 92 and tilts it into horizontal position. At the end of this tilting movement the hook 74 will be engaged with the pawl 75 and further movement of the carriage will cause the cocking member to pivot about its axis 90 to let the knife blade pin 72 ride past the leg 92, and as soon as the pin 72 has disengaged the leg 92, the cocking lever will be snapped back to its normal position while the knife blade assembly remains in cocked position.

Since the knife blade assembly is constructed to sever the tape slightly beyond the terminal end of the tensioning and applying spring 59, and since this spring is pressed toward engagement with the table before the roller 65 engages the same, the end of the tape will be applied across the abutting end edges of the sheets 19 and 20 substantially at the point indicated by the reference character 96 in Figure 1 and in Figure 7. The resiliency of the spring is sufficient to cause adhesion of the tape with the paper and, immediately thereafter, the roller will pass over the tape to firmly press it against the paper, thus causing the tape to smooth out and firmly adhere to the paper. Thus, the roller serves not only to support the carriage during its movement across the table, but it also serves to firmly press the tape against the sheets. During the terminal portion of the splicing movement, after the tape has been severed, the roller 65 will assure that the last portion of the tape is smoothly adhered to the sheets.

To assure that the two sheets of paper are firmly held in position during the splicing operation, the presser foot assembly 15 is provided. The presser foot itself consists of a sheet or strip of spring metal 97 arranged to overlie the marginal edge portions of the abutting sheets adjacent the point at which the tape is initially applied. The presser foot strip 97 is fixed at one end to a shaft 98 journaled between suitable brackets 99 fixed to the undersurface of the table and only one of

which is shown in Figure 1, and the strip projects upwardly therefrom through an opening 100 provided in the table or base and then horizontally to overlie the edge portions of sheets 19 and 20, see Figures 1, 2 and 7. The shaft 98 is provided with a rigid arm 101 extending rearwardly and having its end connected to the lower end of link 102 by means of a tension spring 103 with the upper end of the link 102 passing through an opening in base 10 and being pivoted at 104 to one arm of the bell-crank lever 105 which in turn is pivoted by screw 106 to the cam plate 14. The previously mentioned member 26 which is affixed transversely to the lower end of the guide arm 12 carries a cam 107 which engages the bell-crank 105 and tilts it in such a direction as to tension the spring 103 and cause the presser foot 97 to move into engagement with the sheets to hold the same in place. When the carriage is swung back to its rest or ready position, the bell-crank 105 will pivot by its own weight to relax the spring 103 and permit the presser foot to move up from the table and tilt backward beyond the edge of the sheets 19 and 20 to permit the sheets to be readily placed in position, the cam 107 of course being moved out of engagement with the bell-crank 105 at this time.

It will be understood that, as the carriage 13 moves towards the end of its splicing movement, and before the blade assembly is tripped, the carriage tilts backwardly about the axis of roller 65 so that the spring finger 59 is elevated above the table and there is sufficient clearance between the table and the end of this finger to permit blade 69 to cut the tape when the blade assembly is tripped. The blade cuts the tape at a point above the table, but continued movement of roller 65 over the table presses down the terminal end of the tape.

I claim:

1. A splicing machine comprising a table, means on the table for holding two sheets in edge-to-edge abutting relation, a carriage containing a supply of adhesive tape, means mounting said carriage for movement across said table parallel with the abutting edges of said sheets, a resilient applicator on said carriage for presenting the end of said adhesive tape in overlapping relation with the abutting edge portions of said sheets, a knife mounted on said carriage for cutting said tape, and means controlled by the movement of said carriage a predetermined distance over said table for raising said applicator from engagement with said sheets and for actuating said knife to sever said tape.

2. A splicing machine comprising a table, means on the table for holding two sheets in edge-to-edge abutting relation, a carriage containing a supply of adhesive tape, means mounting said carriage for movement across said table parallel with the abutting edges of said sheets, a resilient applicator on said carriage for feeding said adhesive tape into overlapping relation with the abutting edge portions of said sheets, a spring-activated knife mounted on said carriage for cutting said tape at the end of said applicator, a latch normally holding said knife in cocked position, means controlled by the movement of said carriage a predetermined distance over said table for raising said applicator from engagement with said sheets, and means controlled by further movement of said carriage for releasing said latch.

3. A splicing machine according to claim 2 and including means for guiding said carriage into correct position at the start of its movement across said table, and cocking means embodied in said guiding means for returning said knife to cocked position.

4. A splicing machine comprising a table, means on the table for holding two sheets in edge-to-edge abutting relation, a carriage containing a supply of adhesive tape, means mounting said carriage for movement across said table parallel with the abutting edges of said sheets, an applicator on said carriage for feeding said adhesive tape into overlapping relation with the abutting edge portions

5 of said sheets, a spring-actuated knife mounted on said carriage for cutting said tape at the end of the applicator, a latch normally holding said knife in cocked position, means controlled by the movement of said carriage a predetermined distance over said table for tripping said latch, means for guiding said carriage into correct position at the start of its movement across said table, and cocking means embodied in said guiding means for returning said knife to cocked position.

5. A splicing machine comprising a table, means on said table for holding two sheets to be spliced in edge-to-edge abutting relation, an arm pivoted at its lower end to said table, and a tape carrier, including a combined supporting and tape applying roller, pivotally mounted on the other end of said arm whereby said carrier may be moved from side to side across said table with said roller supporting the same in such movement and rolling over the abutting end edges of the sheets being spliced, said carrier also including means for holding a quantity of splicing tape and means for applying said tape to the sheets ahead of said roller, said means for holding the sheets on the table comprising two parallel rows of locating pins upstanding from the table and engageable through marginal holes along the edges of the sheets, the pins of one row being rigid with the table and the pins in the other row being pivotally mounted upon the table for movement toward and away from said one row of pins, and spring means normally urging said second row of pins away from the first row whereby to effect a stretching and tensioning of the sheets in a direction parallel to the path of movement of said carrier.

6. A splicing machine comprising a table, means on said table for holding two sheets to be spliced in edge-to-edge abutting relation, an arm pivoted at its lower end to said table, and a tape carrier, including a combined supporting and tape applying roller, pivotally mounted on the other end of said arm whereby said carrier may be moved from side to side across said table with said roller supporting the same in such movement and rolling over the abutting end edges of the sheets being spliced, said carrier also including means for holding a quantity of splicing tape, means for applying said tape to the sheets ahead of the roller, a knife for automatically severing said tape at the end of the splicing operation, said knife being movable between a cocked and a cutting position, spring means for snapping the knife from the cocked to the cutting position, and means for releasing said knife from its cocked position, the last mentioned means including a cam engageable with said arm to release the knife when said carriage has been moved across said table.

7. The splicing machine as defined in claim 6, and means fixed to said table adjacent the lower end of said arm for moving said knife to its cocked position during initial movement of the carriage in the splicing operation.

8. A splicing machine comprising a table, means on said table for holding two sheets to be spliced in edge-to-edge abutting relation, an arm pivoted at its lower end to said table about an axis extending transverse to the abutting end edges of the sheets to be spliced, and a tape carrier, including a combined supporting and tape applying roller, pivotally mounted on the other end of said arm whereby said carrier may be moved from side to side across said table with said roller supporting the same in such movement and rolling over the abutting end edges of the sheets being spliced, said carrier also including means for holding a quantity of splicing tape and means for applying said tape to the sheets ahead of said roller.

9. The splicing machine defined in claim 5 including a presser foot for engaging upon adjacent marginal edge portions of the sheets to hold the same against said table as the tape is applied thereto.

10. A splicing machine comprising a table-like base having two parallel rows of upstanding pins mounted thereon for locating and holding two sheets of material in edge-to-edge abutting relation upon the base, an upstanding arm rotatably mounted at its lower end to said

base to one side of said rows of pins and about an axis substantially parallel thereto, a carriage pivoted to the upper end of said arm about an axis parallel to the axis about which the lower end of said arm is rotatable, a tape carrying reel rotatably mounted on said carriage, a pair of spring arms, fixed to the lower depending portion of said carriage and between which tape issued from said reel is fed for application to the sheets to be spliced, a tape-pressing and carriage-supporting roller rotatably carried by said carriage at the lowermost portion thereof for engaging across the abutting ends of the sheets to be spliced immediately behind said spring arms for pressing down the strip of tape applied thereby and for supporting said carriage for guided movement across said base, a severing knife arm pivotally mounted at one end to said carriage and having a knife blade fixed to its free end with the path of movement of said knife blade describing an arc passing just beneath the lower free ends of said spring arms for severing the tape at that point, spring means normally urging said knife blade past its severing position, means for latching the knife blade arm in a cocked position in opposition to said spring means, and means for releasing said latch means to permit said knife blade to sever the tape, the last mentioned means being responsive to the relative angularity between said carriage and said arm to release the latch means near the end of the movement of said carriage as the splicing operation is completed.

11. The assembly as defined in claim 10 wherein one row of said pins is fixed to the table and the other row of pins is pivotally mounted on the table for movement toward and away from said one row of pins, and there being spring means for normally urging the last mentioned row of pins away from the first row so as to tension the sheets in a direction parallel to the path of movement of said carriage.

12. The assembly as defined in claim 11 including a presser foot for engaging those marginal edge portions of the sheets nearest the lower end of said arms to hold

the same against the table as the tape is applied thereto, said presser foot being pivotally mounted on said table and counterbalanced to swing away from the table, and a cam fixed to the lower end of said arm and engageable with mechanism connected to said presser foot for urging the same toward the table as said carriage is moved across the table during the initial stages of a splicing operation.

13. The assembly as defined in claim 11 including a cam plate fixed to said table in upstanding relation thereto adjacent the lower end of said arm but between such arm and the first row of locating pins, said cam plate having a pair of parallel laterally extending flanges affixed thereto and defining a cam track, said roller being journaled upon an axle carried by said carriage with said axle having an extended portion engageable within said cam track during the initial movement of said carriage in the splicing operation and immediately prior to the initial application of tape to said sheets, said latching means for the knife blade arm including a pawl pivoted to said carriage and engageable with said arm when the same is urged to its cocked position, a laterally extending pin fixed to said knife blade arm adjacent the free end thereof and presented, when the knife blade arm is in its released position, so as to pass over the uppermost cam track-defining flange when the carriage is moved in the initial stage of the splicing operation, and a camming lever pivotally mounted on said cam plate in the path of movement of said knife arm pin and having spring means associated therewith to oppose pivotal movement of the camming lever whereby to restrain the knife arm pin as the carriage is moved to effect relative movement between the knife blade arm and the carriage constraining the knife blade arm for movement into its latched position.
